UNITED STATES PATENT OFFICE.

KORNEL PECZ AND KARL REJTÖ, OF BUDAPEST, AUSTRIA-HUNGARY.

FEED-WATER PURIFIER.

1,147,044.

Specification of Letters Patent. Patented July 20, 1915.

Application filed March 5, 1914. Serial No. 822,690.

To all whom it may concern:

Be it known that we, KORNEL PECZ, a subject of His Majesty the Emperor of Austria and King of Hungary, residing at 25⁵ Damjanich utca, Budapest, VII, Austria-Hungary, superintendent, and KARL REJTÖ, a subject of His Majesty the Emperor of Austria and King of Hungary, residing at 40 Ovoda utca, Budapest, VII, Austria-Hungary, controller, have invented a new and useful Feed-Water Purifier, of which the following is a specification.

The invention relates to an apparatus for purifying feed water, and in fact more particularly to apparatus of that kind in which the feed water before being supplied to the boiler is heated so that the salts forming sediment or scale are separated.

One embodiment of an apparatus for purifying feed water according to this invention is illustrated in the accompanying drawings, in which—

Figure 1 is a longitudinal section, and Fig. 2 a cross section on the line 2—2, of Fig. 1 through the purifying apparatus with the neighboring portion of the boiler and its accessories.

A cylindrical container *a* is connected with the boiler *p* by means of a support *b* so that it is arranged above this boiler. The support *b* is hollow and forms a passage from the container *a*, to the boiler *p*, whereby purified water may pass from the container to the boiler. The cylinder *a* has on one end a fixed end wall *s* and on the other end a removable cover *f*. Along the inside of both longitudinal sides rails *i* are fastened upon which rails *k* rest loosely. A number of vertical cells *c*, in the example illustrated 4, are fixed upon these rails *k* and these cells are in communication with one another by means of connecting pipes *e* arranged in staggered relation to one another. The cells *c* are open above, while below they are connected to a common horizontal collecting pipe *d* with which they are in communication through openings *r*. An outlet pipe controlled by a cock *g*, passes from one end of the pipe *d* through the cover *f*.

The rails *k* are fixed to the cover *f* by means of bolts *q* so that after removing the cock *g* and the connecting means joining the cover *f* to the cylindrical container, for example bolts, the cover, together with the rails *k* and the cells *c* resting thereon, and the sediment tube *d* can be withdrawn from

the container *a*. A roller *o* is fastened on the cover *f* and can run on a rail *n* arranged on the boiler *p*. In this manner the withdrawal of the cover *f* with the apparatus connected thereto is facilitated. Water is supplied to the container *a*, through two pipes *v*, *v*, controlled by valves *u*, *u*. These pipes are joined by a fitting *t*, to a pipe *h* which opens into the top of the container *a*. Under the support *b* in the boiler *p* there is a roof-shaped baffle plate *w*.

The feed water purifying apparatus works as follows: If feed water is let into pipe *h* it next passes into the cell *c* below that pipe and then takes its way through the connecting pipes *e* through the whole of the remaining cells *c*. In this way the water is warmed by the steam which passes through the support *b* from the boiler *p* into the container *a* so that the materials forming scale are separated. These materials sink downward in the cells *c* and pass through the holes *r* into the collecting tube *d* which is similarly surrounded by steam so that here also further separation can take place. The water purified in this manner passes through the opening *x* in the last cell *c* over into the container *a* and arrives through the support *b* into the boiler *p* in which it is divided by means of the roof-shaped plate *w*. The sediment collected in the collecting tube *d* is taken out from time to time through the cock *g*. In order to cleanse the interior of the apparatus as has already been said, the cover *f* with the apparatus supported by it is drawn out.

It is preferable to connect the container *a* with the steam space of the boiler *p* by means of a pipe *l* in order to prevent shocks which may be expected upon the introduction of the feed water. The shocks are set up because owing to the cooling due to the entry of the water a sudden fall of pressure is set up locally and this is avoided by supplying steam to the upper part of the cylinder *a*.

The apparatus for purifying feed water described is suitable for application to locomotive as also to stationary boilers.

What we claim is:—

1. An apparatus for purifying feed water consisting of a closed container *a*, cells *c* in the interior of this container, connecting pipes *e* between these cells, a collecting tube *d* to which the different cells are connected, a support *b* attached to the container for

- connection to the boiler, and a tube *h* opening into the container of the water purifier for connection to the feed water pipes, substantially as described.
- 5 2. An apparatus for purifying feed water consisting of a closed container, vertical cells in said container for separating out the scale forming material and a removable cover to which the cells are fixed.
- 10 3. An apparatus for purifying feed water consisting of a closed container, cells in said container, connecting pipes between said cells, a collecting tube to which the cells are connected, side rails to which said cells are fastened, rails mounted on the inside of the
- 15

wall of the container on which said side rails rest, means for fastening said side rails to the removable cover of the container, a support fastened to the container for connection with the boiler and a tube opening into said container for connection to the feed water pipes. 20

In testimony whereof we have signed our names to the specification in the presence of two subscribing witnesses.

KORNEL PECZ.
KARL REJTO.
